UNITED STATES PATENT OFFICE.

HENRY JAMES WAITE, OF PECKHAM, ENGLAND.

LAMP-SHADE CARRIER.

Application filed July 13, 1922. Serial No. 574,834.

To all whom it may concern:

Be it known that I, HENRY JAMES WAITE, a subject of the King of Great Britain and Ireland, residing at 62 Bournemouth Road, 5 Peckham, England, have invented a new and useful Lamp-Shade Carrier, of which the following is a specification.

This invention relates to an improvement in supports or carriers for lamp shades, especially for use in electric lighting.

My improvement consists in the provision at the upper ends of the branch arms of a pair of spring grips pivoted to the said arms, into which upright wires of the shade 15 fit in such a manner that whilst supporting the shade securely, they can at any time be detached, and the shade be removed or replaced.

My invention is illustrated in the accompanying drawings as follows:

Fig. 1 shows the improved lamp shade holder in side elevation.

Fig. 2 shows a shade-wire spring grip at right angles to those shown in Fig. 1 and on 25 an enlarged scale.

Figure 3 shows a plan view of Figure 2.

Figure 4 shows a perspective view of the entire device as attached to a lamp socket and carrying the shade, and

30 Figure 5 shows a perspective view of the carrier in an angular position in relation to the shade.

From the central ring A which fits upon the lamp socket the arms B extend.

35 At the upper end of each arm B, the shade-wire socket C is pivoted at D.

The lower end of the part C is left flat; the upper end is bent over to form a short tube with a longitudinal slot. This tube is sufficiently wide to enable it to receive with 40 slight tension a wire soldered or otherwise attached to an upright of the shade frame at each side whereby the shade is firmly supported.

The curvature of the holder is arranged 45 to suit the kind of shade to which the apparatus is applied, and the tubes or fasteners can be set at any required angle to adapt them to the angle of the supporting wires fixed to the shade frame. With these tubes 50 the shade will be securely retained in the requisite position, but remain detachable at any time.

As shown in the enlarged detail views, Figures 2 and 3, the said members C each 55 consist of a pair of parallel semi-circular sections joined by a flat section so as to form a spring grip adapted to engage directly at any position an arm of the lamp shade as shown by way of example in Figures 4 and 5. 60

What I claim is:

A lamp shade carrier comprising a central ring, a plurality of arms attached to said ring and a member pivoted to the extremity of each of said arms having two jaws 65 each consisting of a pair of parallel semi-circular sections joined by a flat section so as to form a spring grip adapted to engage directly at any position an arm of the lamp shade.

HENRY JAMES WAITE.
